(74) *Attorney, Agent, or Firm*—Townsend and Townsend and Crew LLP

(57) **CLAIM**

The ornamental design for an asymmetrical data device with indentation with shield, as shown and described.

DESCRIPTION

FIG. 1 is a perspective view of an asymmetrical data device with indentation with shield showing a first embodiment of our new design;

FIG. 2 is a top plan view thereof;

FIG. 3 is a left side elevation view thereof;

FIG. 4 is a right side elevation view thereof;

FIG. 5 is a bottom plan view thereof;

FIG. 6 is a front elevation view thereof; and

FIG. 7 is a rear elevation view thereof.

FIG. 8 is a perspective view of a second embodiment of our new design;

FIG. 9 is a top plan view thereof;

FIG. 10 is a left side elevation view thereof;

FIG. 11 is a right side elevation view thereof;

FIG. 12 is a bottom plan view thereof;

FIG. 13 is a front elevation view thereof; and,

FIG. 14 is a rear elevation view thereof.
